UNITED STATES PATENT OFFICE

WILLIAM C. SPIETH, OF GENEVA, OHIO

DESIGN FOR AN ELECTRIC ARC LAMP

Application filed June 10, 1929. Serial No. 31,619. Term of patent 14 years.

To all whom it may concern:

Be it known that I, WILLIAM C. SPIETH, a citizen of the United States, residing at Geneva, in the county of Ashtabula and State of Ohio, have invented a new, original, and ornamental Design for an Electric Arc Lamp, of which the following is a specification, reference being had to the accompanying drawings, which form a part thereof and in which—

Figure 1 is a side elevation of an electric arc lamp showing my new design, while Figure 2 is a front elevation of the electric arc lamp shown in Figure 1.

I claim:

The ornamental design for an electric arc lamp substantially as shown.

WILLIAM C. SPIETH.
